UNITED STATES PATENT OFFICE.

HUGH R. CORLEY, OF LEXINGTON, SOUTH CAROLINA.

LIQUID-DISPENSING APPARATUS.

Application filed September 4, 1925. Serial No. 54,524.

The present invention relates to a coin controlled liquid dispensing apparatus, and aims to provide an apparatus of this nature particularly designed for dispensing gasoline along the roadway in order that an automobilist may drop the proper coin therein and fill his own tank without the necessity of having an attendant for the apparatus. At the present time along the highways of the country most gasoline stations are closed during the night, because the owners thereof cannot afford to maintain an attendant all night long. The automobilist may frequently, however, run out of gasoline along the highway during the night time, and when he does run out of gasoline he occasions the owners of such gasoline stations considerable inconvenience in getting them out of bed. My apparatus, it will be seen, obviates all of these nuisances both to the owner of a gasoline station and to the automobilist.

An important object of the invention is to provide an apparatus of this nature which may be adjusted so as to dispense the proper amount of gasoline for the particular coin adapted to be received in the apparatus, so that the varying prices of gasoline may be compensated for from time to time.

Another very important object of the invention is to provide an apparatus having a structure wherein it is impossible for an automobilist to tinker with the same in such a manner as to obtain more gasoline than he is entitled to in accordance with the coins deposited.

A further very important object of the invention is to provide an apparatus of this nature having an exceedingly simple construction which may be manufactured at a comparatively low cost, one which is durable, reliable, and efficient in operation, not likely to easily become out of order, easy to manipulate, readily adjustable, fool-proof, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:—

Figure 1 is a front elevation of the appa-

ratus embodying the features of my invention.

Figure 2 is an elevation with the door removed showing the operating mechanism 60 of the apparatus,

Figure 3 is a vertical section therethrough,

Figure 4 is an enlarged detail view of the tank emptying valve, 65

Figure 5 is an enlarged transverse section through the piston rod taken substantially on the line 5—5 of Figure 2, looking downwardly.

Referring to the drawing in detail it will be seen that 5 designates a source of supply in the form of a tank embedded in the ground, such as is the common practice, and having associated therewith suitable apparatus for forcing the gasoline in the tank 70 upwardly through the supply pipe 6. The numeral 7 designates a casing having a hinged door 8, with suitable locking means 9 associated therewith. This casing forms a safe for the parts of the apparatus which should be non-accessible to the purchaser, and the casing should be of such strength as to prevent unauthorized access to the interior thereof. This casing 7 is preferably located on the surface of the ground along 75 the highway, above the supply tank 5. The supply pipe 6 rises through the bottom of the casing 7, and extends through the top thereof as is indicated at 6' in Figure 1, to deliver gasoline into a measuring display 80 tank 10, preferably made of glass so that the gasoline collecting therein will be visible, and having the usual protecting means 11 thereabout. This tank 10 is mounted on top 85 of the casing 7 by means of brackets 12 or 90 in any other suitable manner.

A valve 13 is located in the bottom portion of the supply pipe 6 within the casing 7, and will be hereinafter specifically designated as the primary valve. A valve 14 is 100 provided in the pipe 6 intermediate the top and bottom of the casing 7 and will be referred to hereinafter as the secondary valve. A relatively short fulcrum bracket 15 rises from the bottom of the casing 7. A 105 rocker bar 16 has its intermediate portion pivoted as at 17 in the upper end of the bracket 15. One end of this rocker bar is operatively connected with the valve 13 by a link 13', and with the bottom end of a rod 110 18, as is indicated at 19. A piston rod is indicated generally by the letter A and in-

cludes an upper section 20, and a lower section 21, the latter having indicia marked thereon for regulating the adjustment of one section in relation to the other, and also provided with a notch 23. A frame 24 receives the overlapping portions of the sections 20 and 21, and has a set screw 25 therein in order that these sections may be connected in different adjusted positions whereby the 10 length of the piston rod may be varied for controlling the amount of gasoline which will be dispensed upon the operation of the apparatus as will be evident as the description proceeds. The section 20 extends 15 through an opening 26 in the top of the casing 7, and through a stuffing box 27 in the bottom of the tank 10, and is connected to a piston 28 slidable within the tank 10. The section 21 is pivotally engaged at its 20 bottom end to the other end of the rocker bar 16 as is indicated at 29. A dog 30 is pivoted intermediate its ends as at 32 to the extremity of a bracket 33 extending inwardly from one side of the casing 7. This 25 dog 30 has its upper extremity normally held by a spring 31 so as to engage in the notch 23.

A rocker shaft 35 is journaled in the upper portion of the casing 7 and has formed thereon cranks 36, and 37, extending in one direction toward the door 8, and a third crank 38 extending therefrom in an opposite direction or away from the door 8. The rod 18 has a pin and slot connection, as indicated at 39, with the extremity of the first crank 36. A second rod 40 is pivotally engaged with the second crank 38, and is operatively connected with the valve 14. The third crank 37 is pivotally engaged with the 40 upper end of a rod 41, the lower end of which is pivotally engaged with the lower end of the dog 30. A spring 42 normally holds the rock shaft 35 in a predetermined position through the tank 42' as is shown in 45 Figures 2 and 3, that is with the cranks 36, 37, and 38 extending substantially horizontally therefrom, the spring 42 being limited in rocking the shaft by the dog 30 engaging the section 21 through the intermediary of the rod 41, and crank 37. When the parts are disposed as is shown in Figures 2 and 3, the valve 13 is closed, and the valve 14 is open.

The shaft 35 is adapted to be rocked by 55 the crank 43 through the intermediate face of a suitable coin controlled mechanism C of any well known type.

When the shaft 35 is oscillated by the 60 manual throwing of the crank 43 through the suitable coin controlled mechanism C, the following operations take place. As the shaft 35 rotates in a counter-clockwise direction, referring to Figure 3, it will be seen that crank 36 pulls on rod 18 to rock 65 the bar 16 so as to open the valve 13 and

pull downwardly on the piston rod A and move the piston 28 a distance downwardly in the tank 10. As the shaft 35 moves in a clockwise direction, still referring to Figure 3, the crank 36 returns to its normal position, but because of the pin and slot connection 39, does not push upon the rod 18, this movement of the shaft, however, pulls upon the rod 40 to open the valve 14 which was previously closed by crank 38 pushing upon rod 40 in the first movement of the shaft. The first movement of the shaft causes crank 37 to pull upon the rod 41 and release the dog 30 from the notch 23 (it will be understood that the lost motion connection afforded by the pin and slot connection 39 allows the dog 30 to release from the notch 23 before the rod 18 is actually actuated), and the second movement of the shaft, with the aid of spring 31, returns the dog 30 to an engaging position with the notch 23, but of course, not engaged therewith since the notch has moved downwardly because of the downward movement of the piston rod by the first movement of the shaft 35 as previously indicated. Thus, the gasoline is free to flow through the pipe 6 up into the tank 10. As the level of the gasoline rises it engages the piston 28, and moves the same upwardly. The upward movement of this piston pulls upwardly on the piston rod A, rocking the shaft 16 to close the valve 13, and pulling on the rod 18. The proper amount of gasoline should now be in the tank 10. The amount of this gasoline in the tank may be varied in accordance with the price of gasoline at the time of the operation of the apparatus by proper adjustment of the section 20 in relation to section 21, as heretofore indicated, the indicia provided on section 21 being there for this purpose.

An emptying pipe 59 leads from the bottom of the tank 10 through the top of the casing 7, at 60, and out through the side of the casing at 61. A valve 62 is provided in the pipe 59 within the casing, and a valve 63 is provided in the pipe 59 exteriorly of the casing adjacent the end to which is attached the filling hose 64. A rod 65 is operatively connected with the valve 62, and pivotally connected as at 66 to the rocker bar 16, adjacent the end 29 so that when the bar 16 is rocked to pull downwardly on the piston rod A, said rod 65 closes the valve 62 and when the bar 16 is rocked to push upwardly on the piston rod, the rod 65 opens the valve 62. The valve 63 has a novel structure, and particular attention is now called thereto. A V-shaped passage 67 extends longitudinally through the valve body 63, and is bisected by an opening 68 for slidably receiving the valve plate 69 which is provided with a passage 70 at its lower end. The upper end of the valve plate 69 terminates above the valve

body 63. A bracket 71 rises from the valve body 63, and has pivotally mounted on its upper end as at 72 a lever 73, which is pivotally engaged adjacent one end as at 74 with the upper end of the plate 69. The end of the lever 63 is pivotally engaged as at 75 with the upper end of the rod 76 looped as at 77 to extend about the pipe 59. The rod 76 extends into the casing 7, as at 78 and terminates in a transversely disposed loop 79. An auxiliary rod 80 has a looped lower extremity 81 disposed about the bar 16, adjacent the point 66, while its upper end is formed with a transverse loop 82, adapted to receive the rod 76, the loop 79 being adapted to receive the rod 80. A spring 83 is disposed between the loops 79 and 82 to normally hold them separated a predetermined distance.

Supposing the tank 10 to have been filled with the proper amount of gasoline as heretofore described, the automobilist places the hose 64 with the nozzle 84 thereof in the gasoline tank of the automobile, and then depresses the handle portion 85 of the lever 73. The initial movement of this lever partially raises the plate 69, but does not bring the passage 70 in registry with the passage 67, but raises the rod 76 so that the spring 83 raises the rod 80 until the bar 16 is rocked, if this has not been done in the manner heretofore indicated, so as to insure the closing of the valve 13, and the engagement of the dog 30 with the notch 23.

The further movement of the lever merely compresses the spring 83 and continues to lift the valve plate 69 so as to bring the passage 70 into registry with the passage 67 so that the gasoline may flow by gravity from the tank 10 through the pipe 59 and hose 64 into the fuel tank of the automobile. The valve 63, and the associated mechanism prevent the automobilist from obtaining more gasoline than he is entitled to, since as soon as he opens the valve 63, the apparatus in the casing 70 is operated to close the valve 13, and prevent any more gasoline from flowing up into the tank. In actual practice, using a coin control mechanism adapted to receive a silver dollar and to maintain the piston rod A in adjustment so that one dollar's worth of gasoline will be delivered to the tank 10. It is obvious, of course, that any other suitable coin controlled mechanism may be used, that the piston rod A may be adjusted to conform therewith. The piston rod A of course, is further adjustable to compensate for the varying price in gasoline so that the purchaser will always obtain a dollar's worth regardless of the current price of the gasoline.

It will be seen that the apparatus is comparatively simple in its construction, is easy to manipulate both from the standpoint of the owner and the purchaser, is thoroughly

reliable and efficient, is fool-proof, and is well adapted to the dispensing of gasoline by a coin control mechanism, and the manual operation of a purchaser.

The present embodiment of the invention has been disclosed in detail merely by way of example because in actual practice it attains the features of advantage enumerated as desirable in the statement of the invention, and the above description. It will be apparent that numerous changes in the details of construction, and in the combination and arrangement of parts may be resorted to without departing from the spirit or scope of the invention as hereinafter claimed or sacrificing any of its advantages.

Having thus described the invention, what I claim is:

1. A liquid dispensing apparatus including, in combination, a pipe leading from a source of supply, a primary valve in said pipe, a secondary valve in said pipe, a tank at the end of said pipe, a rocker bar having one end operatively connected to the primary valve, a rocker shaft, a crank extending from the shaft, a rod operatively connected with the primary valve and said end of the bar, a pin and slot connection between the rod and the crank, a second crank extending from the shaft in an opposite direction to the first crank, a second rod pivotally engaged with the second crank and operatively connected to the secondary valve, a third crank extending from the shaft in the same direction with the first crank, a pivotally mounted dog, a third rod operatively connected with the dog and the third crank, a piston slidably mounted in the tank, a piston rod including a section connected to the piston and a second section connected to the other end of the bar and provided with a notch engageable by the dog, and means for adjustably connecting the sections, means for rocking the shaft in one direction to cause the first crank to pull the first rod to open the primary valve, to cause the second crank to push the second rod to close the secondary valve, and to cause the third crank to pull the third rod to swing the dog out of engagement with the notch, said first rod simultaneously rocking the bar to pull the piston rod and to move the piston a distance downwardly in the tank, and a spring normally returning the shaft to its initial position to pull the second rod so as to open the secondary valve and return the dog to its engaging position through the third crank and the third rod.

2. A liquid dispensing apparatus including, in combination, a pipe adapted to lead from a source of supply, a primary valve in said pipe, a secondary valve in said pipe, a tank at the end of said pipe, a rocker bar having one end operatively connected to the primary valve, a rocker shaft, a crank ex-

tending from the shaft, a rod operatively connected with the primary valve and said end of the bar, a pin and slot connection between the rod and the crank, a second crank 5 extending from the shaft in an opposite direction to the first crank, a second rod pivotally engaged with the second crank, and operatively connected with the secondary valve, a third crank extending from the 10 shaft in the same direction with the first crank, a pivotally mounted dog, a third rod operatively connected with the dog and the third crank, a piston slidably mounted in the tank, a piston rod including a section 15 connected to the piston, and a second section connected to the other end of the bar and provided with a notch engageable by the dog, and means for adjustably connecting the sections, said means being in the form of 20 a frame disposed about the overlapping ends of the sections and a set screw in the frame to force the sections into frictional engagement with each other, means for rocking the shaft in one direction to cause the first crank 25 to pull the first rod to open the primary valve, to cause the second crank to push the second rod to close the secondary valve and to cause the third crank to pull the third rod to swing the dog out of engagement 30 with the notch, said first rod simultaneously rocking the bar to pull the piston rod and to move the piston a distance downwardly in the tank and a spring normally returning the shaft to its initial position to pull the second rod so as to open the secondary valve and return the dog to its engaging position through the third crank and the third rod. 35

3. A liquid dispensing apparatus including, in combination, a pipe leading from a 40 source of supply, a primary valve in said pipe, a secondary valve in said pipe, a tank at the end of said pipe, a rocker bar having one end operatively connected to the primary valve, a rocker shaft, a crank extending from the shaft, a rod operatively connected 45 with the primary valve and said end of the bar, a loose connection between the rod and the crank, a second crank extending from the shaft in an opposite direction to the first crank, a second rod pivotally engaged with the second crank and operatively connected 50 to the secondary valve, a third crank extending from the shaft in the same direction with the first crank, a pivotally mounted dog, a third rod operatively connected 55 with the dog and the third crank, a piston slidably mounted in the tank, a piston rod provided with a notch engageable by the dog, means for rocking the shaft in one direction 60 to cause the first crank to pull the first rod to open the primary valve, to cause the second crank to push the second rod to close the secondary valve, and to cause the third crank to pull the third rod to swing the 65 dog out of engagement with the notch, said

first rod simultaneously locking the bar to pull the piston rod and to move the piston a distance downwardly in the tank, a spring normally returning the shaft to its initial position to pull the second rod so as to open the secondary valve and return the dog to its engaging position through the third crank and the third rod, and an exhaust pipe leading from the tank, a primary valve in the exhaust pipe, a secondary valve in the 70 exhaust pipe, means operatively connecting the primary valve of the exhaust pipe with the rocker bar so that the initial movement of the rocker bar closes said primary valve of the exhaust pipe and the second movement of the rocker bar opens the same, means connecting the secondary valve of the exhaust pipe with the rocker bar so that when the last mentioned valve is opened, said rocker bar is positively returned to its initial position. 75

4. A liquid dispensing apparatus including in combination, a pipe adapted to lead from a source of supply, a temporary storage tank at the top of the pipe, valve means in the pipe, operating mechanism for the valve means, means for actuating the operating mechanism, an exhaust pipe leading from the tank, a valve in the exhaust pipe, means operatively connecting the operating mechanism with the valve in the exhaust pipe so that the valve is closed when the valve means is open and vice versa, a second valve in the exhaust pipe, and means associated with the second valve to positively 90 cause the closing of the valve means. 95

5. A liquid dispensing apparatus including, in combination, a casing, a door for the casing, lock means associated with the door and casing, a pipe adapted to lead from a 105 source of supply through the bottom of the casing, through the interior of the casing, and through the top of the casing, a primary valve in said pipe within the casing, a secondary valve in said pipe within the 110 casing, a tank mounted on top of the casing, the upper end of said pipe leading into said tank, a rocker bar mounted in said casing and having one end operatively connected to the primary valve, a rocker shaft mounted 115 in said casing, a crank extending from the shaft, a rod operatively connected with the primary valve and said end of the bar, a pin and slot connection between the rod and the crank, a second crank extending from the shaft in an opposite direction to the first crank, a second rod pivotally engaged with the second crank and operatively connected to the secondary valve, a third crank 120 extending from the shaft in the same direction with the first crank, a pivotally mounted dog within the casing, a third rod operatively connected with the dog and the third crank, a piston slidably mounted in the tank, a piston rod including a section connected to 125 130

the piston and extending through the top of the tank and a second section within the casing connected to the other end of the bar and provided with a notch engageable by the 5 dog, and means within the casing for adjustably connecting the sections, means for rocking the shaft in one direction to cause the first crank to pull the first rod to open the primary valve, to cause the second crank 10 to push the second rod to close the secondary valve, and to cause the third crank to pull the third rod to swing the dog out of engagement with the notch, said first rod simultaneously rocking the bar to pull the 15 piston rod and move the piston a distance downwardly in the tank, a spring normally returning the shaft to its initial position to pull the second rod, so as to open the secondary valve and return the dog to its engaging position through the third crank and the third rod, an exhaust pipe leading from the tank, a valve in the exhaust pipe operatively connected with the bar, and a second valve in the exhaust pipe operatively connected with said bar.

6. A liquid dispensing apparatus including in combination, a casing, a pipe adapted 25 to lead from a source of supply and extending through the casing, a temporary storage tank mounted exteriorly of the casing and communicating with one end of the pipe, valve means in the pipe within the casing, 30 operating mechanism within the casing for the valve means, a coin controlled means for actuating the operating mechanism, an exhaust pipe leading from the tank and extending through the casing, a valve in the 35 exhaust pipe within the casing operatively connected with the operating mechanism, a second valve in the exhaust pipe located exteriorly of the casing, an operating lever for the second valve, a rod engaged with the 40 operating lever and extending into the casing and terminating in a loop, a second rod operatively connected with the operating mechanism and having a loop for receiving the first rod, the loop of the first rod receiving 45 the second rod, and a spring disposed between the loops whereby the opening of the second valve causes the positive closing of the valve means.

7. A liquid dispensing apparatus including, in combination, a pipe leading from a source of supply, a primary valve in said pipe, a secondary valve in said pipe, a tank at the end of said pipe, a rocker bar having one end operatively connected to the primary valve, a rocker shaft, a crank extending from the shaft, a rod operatively connected with the primary valve and said end of the bar, a pin and slot connection between the rod and the crank, a second crank extending from the shaft in an opposite direction to the first crank, a second rod pivotally engaged with the second crank and operatively connected to the secondary valve, a third crank extending from the shaft in the same direction with the first crank, a pivotally mounted dog, a third rod operatively connected with the dog and the third crank, a piston slidably mounted in the tank, a piston rod engaged with the piston and the bar, means for rocking the shaft in one direction to cause the first crank to pull the first rod to open the primary valve, to cause the second crank to push the second rod to close the secondary valve, and to cause the third crank to pull the third rod to swing the dog out of engagement with the notch, said first rod simultaneously rocking the bar to pull the piston rod and move the piston a distance downwardly in the tank, a spring normally returning the shaft to its initial position to pull the second rod, so as to open the secondary valve and return the dog to its engaging position through the third crank and the third rod, an exhaust pipe leading from the tank, a valve in the exhaust pipe operatively connected with the bar, a second valve in the exhaust pipe, a rod section, a second rod section, a resilient means between the sec-

50 crank, a pivotally mounted dog, a third rod operatively connected with the dog and the third crank, a piston slidably mounted in the tank, a piston rod engaged with the piston and the bar, means for rocking the shaft in one direction to cause the first crank to pull the first rod to open the primary valve, to cause the second crank to push the second rod to close the secondary valve, and to cause the third crank to pull the third rod to swing the dog out of engagement with the notch, said first rod simultaneously rocking the bar to pull the piston rod and move the piston a distance downwardly in the tank, a spring normally returning the shaft to its initial position to pull the second rod, so as to open the secondary valve and return the dog to its engaging position through the third crank and the third rod, an exhaust pipe leading from the tank, a valve in the exhaust pipe operatively connected with the bar, and a second valve in the exhaust pipe operatively connected with said bar.

8. A liquid dispensing apparatus including, in combination, a pipe leading from a source of supply, a primary valve in said pipe, a secondary valve in said pipe, a tank at the end of said pipe, a rocker bar having one end operatively connected to the primary valve, a rocker shaft, a crank extending from the shaft, a rod operatively connected with the primary valve and said end of the bar, a pin and slot connection between the rod and the crank, a second crank extending from the shaft in an opposite direction to the first crank, a second rod pivotally engaged with the second crank and operatively connected to the secondary valve, a third crank extending from the shaft in the same direction with the first crank, a pivotally mounted dog, a third rod operatively connected with the dog and the third crank, a piston slidably mounted in the tank, a piston rod engaged with the piston and the bar, means for rocking the shaft in one direction to cause the first crank to pull the first rod to open the primary valve, to cause the second crank to push the second rod to close the secondary valve, and to cause the third crank to pull the third rod to swing the dog out of engagement with the notch, said first rod simultaneously rocking the bar to pull the piston rod and move the piston a distance downwardly in the tank, a spring normally returning the shaft to its initial position to pull the second rod, so as to open the secondary valve and return the dog to its engaging position through the third crank and the third rod, an exhaust pipe leading from the tank, a valve in the exhaust pipe operatively connected with the bar, a second valve in the exhaust pipe, a rod section, a second rod section, a resilient means between the sec-

tions, one section engaged with the rocker bar, a lever for operating the second exhaust valve, said other section being engaged with said lever so that when said 5 lever is moved to open said second exhaust valve said bar is rocked to insure the engagement of said dog with said notch.

9. A liquid dispensing apparatus, including in combination, a casing, a supply pipe 10 leading from a source of supply and extending through the casing, a primary valve in said pipe within the casing, a secondary valve in said pipe within the casing, a tank on the exterior of the casing and communicating 15 with the end of the pipe, a rocker bar pivotally mounted intermediate its ends within the casing and having one end operatively connected to the primary valve, a rocker shaft journaled in the casing, a crank extending from the shaft, a rod operatively connected with the primary valve and said end of the bar, a loose connection between the rod and the crank, a second crank extending from the shaft in an opposite direction to the first crank, a second rod pivotally engaged with the second crank, and operatively connected to the secondary valve, a third crank extending from the shaft in the same direction with the first crank, a pivotally mounted dog within the casing, a third rod operatively connected with the dog and the third crank, a piston slidably mounted in the tank, a piston rod extending through the casing and connected to the piston and to the other end of the bar and having a notch within the casing engageable by the dog, means for 20 rocking the shaft in one direction to cause the first crank to pull the first rod to open the primary valve, to cause the second crank to push the second rod to close the secondary valve, and to cause the third crank to pull the third rod to swing the dog out of engagement with the notch, said first rod simultaneously rocking the bar to pull the piston rod and move the piston a distance downwardly in the tank, a spring normally 25 returning the shaft to its initial position to pull the secondary rod so as to open the second valve and return the dog to its engaging position through the third crank and third rod, an exhaust pipe leading from the tank through the casing, a valve in the exhaust pipe within the casing, an operating rod attached to the exhaust valve and to the rocker bar so that said exhaust valve will be 30 open when said secondary valve is closed and vice versa, a second valve in the exhaust pipe exteriorly of the casing, a lever for operation of the second valve, a rod engaged with the lever and extending into the casing and including sections, a spring between the 35 one section of the last mentioned rod so that when said lever is operated to open the second valve one section of the last mentioned rod is pulled so that the spring will pull the other section of the last mentioned rod to rock the bar to insure the closing of the secondary valve and the engagement of the dog with the notch in the piston rod and further 40 swinging of the lever will cause further tensioning of the spring and allow the second valve to be opened.

10. A liquid dispensing apparatus including, in combination, a casing, a pipe adapted to lead from a source of supply and extending through the casing, a tank exteriorly

mounted on the casing and communicating 65 with said pipe, a primary valve in said pipe within the casing, a secondary valve in the pipe within the casing, a rocker bar pivotally mounted intermediate its ends within the casing and having one end operatively connected to the primary valve, a rocker shaft journaled in the casing, a crank extending from the shaft, a rod operatively connected with the primary valve and said end of the bar, a loose connection between the rod and the crank, a second crank extending from the shaft in an opposite direction to the first crank, a second rod pivotally engaged with the second crank, and operatively connected to the secondary valve, a third crank extending from the shaft in the same direction with the first crank, a pivotally mounted dog within the casing, a third rod operatively connected with the dog and the third crank, a piston slidably mounted in the tank, a piston rod extending through the casing and connected to the piston and to the other end of the bar and having a notch within the casing engageable by the dog, means for 70 rocking the shaft in one direction to cause the first crank to pull the first rod to open the primary valve, to cause the second crank to push the second rod to close the secondary valve, and to cause the third crank to pull the third rod to swing the dog out of engagement with the notch, said first rod simultaneously rocking the bar to pull the piston rod and move the piston a distance downwardly in the tank, a spring normally 75 returning the shaft to its initial position to pull the secondary rod so as to open the second valve and return the dog to its engaging position through the third crank and third rod, an exhaust pipe leading from the tank through the casing, a valve in the exhaust pipe within the casing, an operating rod attached to the exhaust valve and to the rocker bar so that said exhaust valve will be open when said secondary valve is closed and vice versa, a second valve in the exhaust pipe exteriorly of the casing, a lever for 80 operation of the second valve, a rod engaged with the lever and extending into the casing and including sections, a spring between the one section of the last mentioned rod so that when said lever is operated to open the second valve one section of the last mentioned rod is pulled so that the spring will pull the other section of the last mentioned rod to rock the bar to insure the closing of the secondary valve and the engagement of the dog with the notch in the piston rod and further 85 swinging of the lever will cause further tensioning of the spring and allow the second valve to be opened.

In testimony whereof I affix my signature.

HUGH R. CORLEY.
